UNITED STATES PATENT OFFICE.

GEORGE F. BALLOU, OF NEW YORK, N. Y., ASSIGNOR TO ARTHUR BERGH, OF NEW YORK, N. Y.

RAZOR-SHARPENING DEVICE.

Application filed February 27, 1922. Serial No. 539,633.

This invention relates to stropping devices for razor blades, particularly safety razor blades, and has for an object to provide an improved mechanical stropping device with which razor blades may be effectively and satisfactorily stropped by novices within a minimum of time, and which is exceedingly compact, simple and durable in construction, attractive in appearance, and inexpensive. Other objects and advantages will be apparent from the following description of an embodiment of the invention, and the novel features will be particularly pointed out in claims.

The invention comprehends a moving stropping surface and a carrier for detachably mounting razor blades for movement into and out of stropping relation with the moving stropping surface. The carrier is mounted so as to permit the cutting edge of the blade to contact during its entire length with the stropping surface. I also contemplate providing a guiding device for the carrier by means of which the cutting edge of the blade cannot be brought into contact with the stropping surface unless it is first brought into a position in which it is parallel with the portion of the stropping surface with which it will engage, and by means of which displacement of the blade from proper stropping position is prevented while in contact with or in close proximity to the stropping surface. The invention also comprehends various details and arrangements which will be explained in the following description.

In the drawings, Fig. 1 is a perspective view of an embodiment of my invention. Figs. 2, 3 and 4 are similar medial sectional views of the device with the blade holder in different operable positions; Figs. 5 and 6 are fractional sectional details.

In the illustrated embodiment, a suitable base plate 1 is provided with spaced bearings 2 in which the bearing extensions 3 of a stropping member 4 are rotatably mounted. One of the bearings 3 of the member 4 is extended and provided with a suitable operating member 5 through the medium of which the stropping member may be rotated. The stropping member is provided with a stropping surface 6 which may be provided by winding the member, that in this embodiment is cylindrical, helically with a strip of leather, canvas or other suitable stropp-

ing material so as to avoid abrupt seams.

A blade carrier 7 terminates at one end in a spherical ball 8 which is detachably and yieldingly clamped in a socket device 9 by a resilient or spring clamp member 10. The socket device acts as a hinge element forming an articulated connection between the carrier and the base, and permits rotation of the carrier upon its axis and also movement of its other end toward and from the stropping member. The other or free end is provided with a spring clamp device 11 which detachably mounts a razor blade 12 of the safety razor type, one of the members of the clamp device having pins 13 which enter the usual apertures in certain types of safety razor blades 13 and hold the blades securely against displacement in the clamp device. The relatively movable member of the clamp device is hinged by suitable ears 14 to a pin 15 carried by the other member of the clamp, and a helical spring 16 surrounding the pin 15 resiliently presses the movable member toward the relatively non-movable member to grip the interposed razor blade 12 with its cutting edge portion projecting from the clamping device. When the carrier with its blade is brought toward the cylinder 4 the cutting edge of the blade will be brought into stropping contact with the stropping surface of the cylinder, and the carrier is free to rotate so as to bring all points in the cutting edge of the blade in contact with the stropping surface, which in effect means that the cutting edge must be parallel with the portion of the stropping surface with which it engages.

It is desirable to prevent lateral or side-wise movement of the carrier and blade during the stropping operation, and to prevent movement of the blade into contact with the surface of the cylinder when not parallel with the portion of the surface to be engaged. Accordingly an intermediate portion 17 of the carrier is of non-circular cross section which is accomplished by flattening the carrier somewhat. An upstanding lug 18 on the socket device is provided with a vertically extending slot 19 of a size and shape freely to receive edgewise the flattened portion 17 of the carrier without loose play, whereby the slot will guide the carrier toward the cylinder with the cutting edge of the blade parallel with the portion of the stropping surface to be engaged, and

will prevent lateral or sidewise movement of the blade during the stropping operation. To facilitate the entrance of the edge of the carrier into the slot, the upper ends of the 5 slot may be divergent.

In the use of the device, the carrier is swung upwardly out of the slot 19 and rotated to bring the wide portion across the slot as shown in Figs. 3 and 6 and the carrier 10 is then allowed to rest upon the lug 18, in which position the blade is out of contact with the stropping surface of the cylinder. By manipulating the clamping device a 15 razor blade which it is desired to sharpen may be secured to the carrier. The carrier may then be rotated about its longitudinal axis to bring the flattened portion edgewise to the lug 18 and is then allowed to enter the slot and move towards the cylinder to 20 bring the cutting edge of the blade into stropping contact with the stropping surface of the cylinder, as shown in Figs. 2, 4 and 5. Rotation of the cylinder will move the stropping surface beneath the cutting 25 edge and effectively strop the same. After a number of rotations of the cylinder, the carrier may be raised above the lug 18, rotated about its longitudinal axis through approximately 180° and again into contact 30 with the cylinder to strop the other face of the cutting edge. If desired the carrier may be detached from the socket device by pulling the same therefrom, the spring member 10 yielding to permit of this detachment or a re-insertion. The bottom of 35 the slot acts as a stop to prevent downward movement of the carrier to an extent which would permit flexing of the blade in contact with the cylinder sufficiently to render the 40 stropping ineffective or to break the blade.

It will be understood that various changes in the details and arrangements herein described and illustrated for the purpose of explaining the nature of the invention may 45 be made by those skilled in the art within the principle and scope of the invention.

Having described my invention, what I claim is:

1. In a stropping device, a base, a stropping member rotatably mounted on said 50 base and having on its periphery a stropping surface, a blade carrier for detachably mounting a razor blade, a hinge element carried by the base and to which the carrier has an articulated connection for 55 rotary movement and for movement toward and from the member, whereby the blade may be brought into stropping relation with said member with the cutting edge in contact with the stropping surface along its 60 entire length, said carrier having a portion of non-circular cross section, and a guide carried by the base and having a slot to receive the non-circular portion of the carrier 65 as the latter moves toward the member and

hold the carrier against rotation and with the cutting edge of the blade parallel with the stropping surface which it engages.

2. In a stropping device, a base, a stropping member rotatably mounted on said 70 base and having a stropping surface, a blade carrier for detachably mounting a razor blade and terminating in a ball end, a spring clamp socket device carried by the base for detachably receiving the ball end 75 whereby the carrier may move toward and from the member to bring the cutting edge of the blade against the stropping surface and also rotate to bring all parts of the cutting edge in contact with the stropping surface, said carrier having a portion of non- 80 circular cross section, and a guide carried by the base and having a slot to receive the non-circular portion of the carrier as the latter moves toward the member and hold the carrier against rotation and with the cutting edge of the blade parallel with the stropping surface which it engages.

3. In a stropping device, a sheet metal 85 base having spaced upstanding arms, a stropping member rotatably mounted in said arms, means enabling manual operation of said member, a carrier hinged universally to said base and movable toward and from the member, said carrier having 90 means for detachably mounting a razor blade for movement with the carrier into and out of contact with said member, and a guide device coacting with said carrier for preventing movement of the carrier to carry the blade into stropping engagement with said member when the cutting edge of the blade is not parallel with the stropping surface which it would engage.

4. In a stropping device, a sheet metal 105 base having spaced upstanding arms, a stropping member rotatably mounted in said arms, means enabling manual operation of said member, a carrier hinged universally to said base and movable toward and from the member, said carrier having means 110 for detachably mounting a razor blade for movement with the carrier into and out of contact with said member, an abutment carried by the base beneath the carrier and having a slot therein into which the carrier moves in carrying a blade into stropping engagement with said member, said carrier at the portion engaging the abutment being non-circular in cross section and of such dimensions that when presenting the blade flatwise to said member it may enter said slot and when not presenting the blade flatwise, it cannot enter the slot far enough to let the blade engage the stropping member.

5. In a stropping device, a support, a stropping member carried by said support, a blade carrier adapted removably to mount a razor blade universally hinged to said support for movement toward and from the 130

member whereby the cutting edge of a mounted blade may be carried into stropping relation with said member, and an upright on said support beneath the carrier and having a slot therein extending in the direction of movement of the carrier in conducting a blade into stropping relation with said member, said carrier having unequal cross sectional dimensions at the point where it engages said upright, with the minimum dimension such as to enter the slot when the blade is substantially parallel with the surface portion of the stropping member it would engage, and with the maximum dimension greater than the width of the slot and extending across and preventing its entrance to the slot and thereby movement of the blade into contact with the said member, when the mounted blade is not parallel with the said surface portion of the member.

6. In a sharpening device, a sheet metal base having upright tongues at one end, a sharpening member rotatably mounted in said tongues, a strip of sheet spring metal secured at the other end of the base and extending toward the sharpening member, the outer end of said strip being turned back upon itself to form a spring clamp, and a blade carrier having a pivot end yieldingly held in said clamp, and movable toward and from the sharpening member.

7. In a sharpening device, a sheet metal base having upright tongues at one end, a sharpening member rotatably mounted in said tongues, a strip of sheet spring metal secured at the other end of the base and extending toward the sharpening member, the outer end of said strip being turned back upon itself to form a spring clamp and a blade carrier having a pivot end yieldingly held in said clamp, and movable toward and from the sharpening member, the inner end of the strip being turned upwardly below the carrier and having a vertical slot which the carrier must enter before a blade carried thereby can engage the sharpening member.

8. In a sharpening device, a sheet metal base having upright tongues at one end, a sharpening member rotatably mounted in said tongues, a strip of sheet spring metal secured at the other end of the base and extending toward the sharpening member, the outer end of said strip being turned back upon itself to form a spring clamp, and a blade carrier having a ball end yieldingly held in said clamp and universally movable therein, whereby the carrier may rotate about the longitudinal axis and also move toward and from the sharpening member to carry selectively either face of a cutting edge against the said member.

9. In a sharpening device, a sheet metal base having upright tongues at one end, a

sharpening member rotatably mounted in said tongues, a strip of sheet spring metal secured at the other end of the base and extending toward the sharpening member, the outer end of said strip being turned back upon itself to form a spring clamp, and a blade carrier having a ball end yieldingly held in said clamp and universally movable therein, whereby the carrier may rotate about the longitudinal axis and also move toward and from the sharpening member to carry selectively either face of a cutting edge against the said member, the inner end of the strip being turned upwardly below the carrier and having a vertical slot which the carrier must enter before a blade carried thereby can engage the sharpening member.

10. In a sharpening device, a sheet metal base having upright tongues at one end, a sharpening member rotatably mounted in said tongues, a strip of sheet spring metal secured at the other end of the base and extending toward the sharpening member, the outer end of said strip being turned back upon itself to form a spring clamp, and a blade carrier having a ball end yieldingly held in said clamp and universally movable therein, whereby the carrier may rotate about the longitudinal axis and also move toward and from the sharpening member to carry selectively either face of a cutting edge against the said member, the inner end of the strip being turned upwardly below the carrier and having a vertical slot which the carrier must enter before a blade carried thereby can engage the sharpening member, the carrier at the point entering the slot being elongated in cross section with its minimum dimension not greater than the width of the slot and its maximum dimension greater than the width of the slot, whereby the carrier can only enter the slot when in diametrically opposite positions about its own axis and with the blade parallel with the portion of the surface of the member which it would engage.

11. In a sharpening device, a base, a sharpening member carried by the base, a blade carrier hinged to the base for movement toward and from the member and thus carry the cutting edge of a blade into and out of sharpening relation to said member, an abutment upon said base having a guiding slot into which the carrier must move in carrying a blade into sharpening relation to said member, the bottom of the slot limiting the movement of the carrier toward the member in order to prevent the application of undue flexing stress upon the blade by its pressure upon said member.

In testimony whereof I have hereunto set my hand.

GEORGE F. BALLOU.
